[57] CLAIM

The ornamental design for an asparagus box, as shown and described.

DESCRIPTION

FIG. 1 is a front elevational view of an asparagus box showing our new design, the rear elevational view being the mirror image thereof;

FIG. 2 is a perspective view thereof;

FIG. 3 is a left side elevational view thereof, the right side elevational view being identical thereto; and,

FIG. 4 is a top plan view thereof.
